UNITED STATES PATENT OFFICE

125,786

DESIGN FOR A ROTARY BRUSH FOR VACUUM CLEANERS

Theodore A. Schaad, Detroit, Mich., assignor to
Eureka Vacuum Cleaner Company, Detroit,
Mich., a corporation of Michigan

Application May 15, 1940, Serial No. 92,393

Term of patent 14 years

To all whom it may concern:

Be it known that I, Theodore A. Schaad, a citizen of the United States of America, residing at Detroit, in the county of Wayne and State of Michigan, have invented a certain new, original, and ornamental Design for a Rotary Brush for Vacuum Cleaners, of which the following is a specification, reference being had therein to the accompanying drawing, forming a part thereof, wherein:

The figure is a side elevational view of a rotary brush for vacuum cleaners showing my new design.

The opposite side of the two ends presents, in

reverse, the same appearance as the two ends shown.

The dominant feature of this design consists in providing the cylindrical brush body with spirals extending partially around the brush body in opposite directions from the approximate center of the brush body to the ends of the latter and having a color different from the color of the brush body.

I claim:

The ornamental design for a rotary brush for vacuum cleaners, substantially as shown and described.

THEODORE A. SCHAAD.
